US00D691570S

(12) **United States Design Patent**
Fleischer et al.

(10) **Patent No.:** **US D691,570 S**
(b4) **Date of Patent:** **** Oct. 15, 2013**

(54) **IMAGING DEVICE**

(75) Inventors: **Bianca Fleischer**, Santa Monica, CA (US); **Etienne Iliffe-Moon**, Newbury Park, CA (US); **Adil Ali**, Newbury Park, CA (US); **Shanshan Li**, Fort Collins, CO (US); **Charles E. Schinner**, Windsor, CO (US); **Edward George Trick**, Louisville, CO (US)

(73) Assignee: **Hewlett-Packard Development Company, L.P.**, Houston, TX (US)

(**) Term: **14 Years**

(21) Appl. No.: **29/419,410**

(22) Filed: **Apr. 27, 2012**

(51) LOC (9) Cl. **14-02**

(52) U.S. Cl.

USPC **D14/121**

(58) **Field of Classification Search**

USPC D14/421-425; D18/55, 49, 46, 40, D18/36-39, 41, 44, 45, 47, 48, 50-54, 56; 235/462, 455, 470, 462, 43, 482, 483; 358/474, 486, 488, 496, 497, 498, 452, 358/449, 451, 453, 1,13; 318/685, 696; 355/81, 75; 399/405, 367, 379, 380; 382/217; 715/209, 222, 226, 274; 400/613, 613.1-613.4, 690.1-690.4, 400/691-694

(57) **CLAIM**

The ornamental design for an imaging device, substantially as shown and described.

DESCRIPTION

FIG. 1 is a right-front perspective view of an imaging device, shown illustratively with a pulled out keyboard in unclaimed broken lines;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a right-front perspective view of the imaging device, shown illustratively with a stowed away keyboard in unclaimed broken lines.

Broken lines and portions contained within broken lines are not claimed.

1 Claim, 8 Drawing Sheets
